IGNITION DEVICE FOR HIGH-POWER ARC LAMPS

Heinrich Beck, Meiningen, Germany, assignor to
firm Carl Zeiss, Jena, GermanyApplication October 20, 1931, Serial No. 569,954
In Germany October 23, 1930

4 Claims. (Cl. 176—55)

I have filed an application in Germany, October 23, 1930.

High-power arc lamps of the kind specially used as search lights have been ignited in the 5 manner common with arc lamps, namely by making the electrode tips touch each other and part. However, with arc lamps of specially high intensities, viz. 200 to 500 amperes and more, this kind of ignition entails certain disadvantages. When 10 the carbon ends touch each other the current rises too far above the normal strength and assumes high values. Moreover, recesses are in most cases burnt into the carbons when they are in touch with each other, which means that the 15 crater surfaces have to suffer an undesirable deformation. Another drawback is that the carbon ends may splinter. There is still a further disadvantage which consists therein that the usual ignition device hardly permits of effecting 20 the ignition within a very short time. The ever increasing demands upon high-power search lights, especially upon those for military purposes, require ignition periods ranging down to 0.1 second, the chief requirement being that during 25 the working of the search light any rupture of the light arc, which may be caused for instance by shooting off a heavy gun or by a detonation, is succeeded so quickly by the re-ignition that any interruption of the light is hardly noticeable. With arc lamps of very strong currents any 30 rapid ignition is possible only with great difficulty. In lamps of this kind the carbon as well as the carbon holder are rather heavy, which, together with purely mechanical reasons, makes it 35 difficult to effect the reciprocating movements for the ignition within a short period. Greater difficulties are encountered when the electrodes are guided in electrode heads. In this case also the heavy electrode head must be moved to and 40 fro, which means that the above mentioned disadvantage is even more pronounced, or the electrode is to be displaced in the carbon holder. However, when displacing the carbon holder, a considerable friction must be overcome, which is 45 due to the necessary contact pressure, this friction representing a special difficulty with respect to quick ignition movements.

The present invention overcomes all these disadvantages by using a special auxiliary ignition 50 electrode and by giving the current in the ignition circuit such a strength that removing the ignition electrode from the negative main electrode causes the arc to jump by itself to the positive main electrode without the ignition electrode touching this 55 main electrode.

The accompanying drawing represents in front elevation, partly in a section, a constructional example of an ignition device according to the invention.

The positive and the negative electrode of the 60 lamp and the ignition electrode are designated *a*, *b*, and *c*, respectively. The ignition electrode *c* moves easily in a guide *d* and is fixed to a lever system *e* connected by means of a lever *f*¹ to the armature *f*² of an electro-magnet *f* which a tension spring *f*³ gives the position represented in the drawing. At its one end the lever *f*¹ is fixed to a piston *g* which fits narrowly into and emerges in a dash-pot *g*¹ having below an aperture *g*². The ignition electrode *c* is connected by means 70 of a lead *c*¹ to the positive supply lead of the lamp. Between this positive lead and the ignition electrode is connected a current limiting resistance *c*².

When in this device the lamp is switched on, the magnet *f* attracts its armature *f*² and the 75 ignition electrode *c* is taken away from the negative electrode *b*, a light arc being formed which, when the current in the ignition circuit is strong enough, at once jumps over to the positive main electrode *a* without the ignition electrode touching this main electrode. When the armature *f*² reassumes its original position, the movement of the ignition electrode is strongly damped towards its end by the piston *g*, the ignition electrode thus being prevented from striking too strongly 85 against the negative electrode *b*.

With the lamps according to the invention the ignition light arc is not required to be of the length of the main arc, an ignition already taking place when the light arc is only a few millimeters long. Apparently this phenomenon is due to the fact that, when the current is sufficiently strong, the negative electrode repels the electrons (also when covered with substance) in a cathode-ray like manner at right angles to the 95 surface, regardless of the position of the auxiliary anode. These electrons strike the main anode, and the ignition is effected immediately. This ignition process is therefore not to be compared either with those caused by the known ignition devices in arc lamps of the usual weak currents, in which it has been tried to make the light arc ignite by drawing it to the positive carbon by means of an auxiliary electrode, or with devices in which an ignition rod is made to lie 105 between carbons, thus causing them to be short-circuited, and effects the ignition by combining the two arising light arcs. With the first said device the ignition is caused by the auxiliary ignition arc being elongated until the light arc 110

flows round the main anode and partakes of the conduction of current. In this case the auxiliary ignition arc must be formed comparatively slowly as, otherwise, it would break without reaching the length required for the ignition. All this is quite different with the object of the present invention. If the space between the main electrodes amounts for instance to 37 millimeters, the ignition takes place already when the auxiliary light arc has a length of, for instance, 1 to 4 millimeters. The negative light arc shooting out in a cathode-ray like manner requires a definite high strength of current. This strength depends partly upon the nature of the electrode material and partly upon the space between the main electrodes, for, the greater this space the more strongly the electrons must be repelled in order to reach the anode with sufficient speed. By way of example there may be remarked that with a definite carbon material and a space of 37 millimeters between the electrodes the strength of current of the ignition light arc with which the novel phenomenon still could be noticed, amounted to approximately 40 amperes. Above this value the phenomenon appeared always, below this value the ignition became rather uncertain and finally ceased altogether.

The strength of the ignition current can be adjusted to the desired degree by means of a resistance. This resistance may be dispensed with if the thin ignition electrode, which may be of carbon, metal or any other conductive material, offers a sufficient resistance. The current of the ignition light arc is generally given a strength not surpassing the normal strength of the lamp current, which is in general considerably higher than the above mentioned lowest strength of the ignition current. As will be explained further below, the new device permits to attain extraordinarily short ignition periods, and for this reason it is possible to reduce the impulse of the ignition current to the desired degree by using a choking coil instead of the resistance. If, as in the example represented in the drawing, the ignition electrode is moved by means of a main current magnet, the self-induction of this magnet suffices in most cases to reduce the strength of the ignition current to a degree below that of the lamp current. The dangerous impulse of the ignition current, which, with a lamp of for instance 450 amperes and the kind of ignition used hitherto, is caused by the touching of the two electrodes and may amount to one and a half and more of the normal strength of current, is therefore completely eliminated in the new device. Moreover, the positive crater never can be damaged by electrode contact. Also any deformation of the negative crater is not to be feared, since with a lamp of for instance 450 amperes the strength of the current of the ignition arc may lie considerably below this value. With the device according to the invention it is further possible to attain extremely short ignition periods. The ignition carbon conducting current only for a very short time, it is possible to make this carbon very thin and consequently light. For the same reason specially strong current supply leads are not required. Further, the carbon can move easily in its guides. The light weight of the carbon and its mobility permit to move the ignition carbon exceedingly quickly, and the ignition periods can be reduced to 0.2 to 0.1 second. Such short ignition periods make it hardly possible to perceive any rupture of the light arc,

such rupture being perceptible only by a slight fluctuation of light. The new ignition device even permits to eventually burn the search light without a cover glass, since in the case of the influence of the wind breaking the light arc the re-ignition is effected so quickly that hardly any interruption is noticed. Such short ignition periods requiring the ignition carbon to move extraordinarily quickly, special means have to be provided in order to prevent the said carbon from striking too strongly against the main electrode. For this reason, as mentioned already, the speed of the ignition carbon is strongly reduced immediately before this carbon strikes against the electrode. This can be effected in different manners. If the ignition carbon is moved by means of a magnet, the reduction of speed can be effected for instance in the way suggested by the drawing, viz. by means of a dash pot. If the ignition carbon is moved by means of an electric motor, its speed can be suddenly reduced by a short-circuit brake, &c.

The position of the ignition carbon is in general of no importance, since an ignition takes place in nearly any position of this carbon. However, with a view to avoid any undesirable additional losses of light, the ignition carbon is conveniently given in search lights such a position that this carbon as well as the levers are in the shade as far as possible.

I claim:

1. In a high-power arc lamp, an anode, a cathode, and a third, auxiliary, electrode, the auxiliary electrode being movable and so disposed that it can touch the cathode only, and means bringing the auxiliary electrode in and out of contact with the cathode, a resistance in the circuit to which the anode and the auxiliary electrode are connected which is so high that withdrawing the auxiliary electrode from the cathode gives rise to a light arc between the auxiliary electrode and the cathode, this light arc having such strength that the negative flame emanating from the cathode reaches the anode and causes the ignition without the auxiliary electrode touching the anode.

2. In a high-power arc lamp, an anode, a cathode, and a third, auxiliary, electrode, the auxiliary electrode being movable and so disposed that it can touch the cathode only, and means bringing the auxiliary electrode in and out of contact with the cathode, a resistance in the circuit to which the anode and the auxiliary electrode are connected which is so high that withdrawing the auxiliary electrode from the cathode gives rise to a light arc between the auxiliary electrode and the cathode, this light arc having such strength that the negative flame emanating from the cathode reaches the anode and causes the ignition without the auxiliary electrode touching the anode, the resistance and the self-induction in the said circuit being so high that the tension of the current of the light arc formed in this circuit is at most only slightly higher than the normal tension of the arc lamp.

3. In an arc lamp according to claim 1, means for strongly reducing the speed of the auxiliary electrode before this auxiliary electrode reaches the cathode.

4. In an arc lamp according to claim 1, the auxiliary electrode and the said means being disposed in the space below the anode and the cathode.

HEINRICH BECK.
